UNITED STATES PATENT OFFICE.

HENRY P. KING, OF OSGOOD, INDIANA.

STORAGE BATTERY.

SPECIFICATION forming part of Letters Patent No. 710,870, dated October 7, 1902.

Application filed May 16, 1902. Serial No. 107,638. (No model.)

To all whom it may concern:

Be it known that I, HENRY P. KING, a citizen of the United States, residing at Osgood, in the county of Ripley and State of Indiana, 5 have invented a new and Improved Storage Battery, of which the following is a full, clear, and exact description.

My invention relates to storage batteries, my purpose more particularly being to produce a neat, compact, and reliable form of storage battery in which the battery-plates are protected to some extent by their form.

An additional object of my invention is to produce a storage battery of comparatively great power and of a form convenient for housing in an ordinary battery-jar.

Reference is to be had to the accompanying drawings, forming a part of this specification, in which similar characters of reference indicate corresponding parts in all the figures.

Figure 1 is an elevation, partly in section, showing a cell of my battery, the jar being indicated by dotted lines. Fig. 2 is a plan view of the battery-plates and their immediate connections removed from the jar, and Fig. 3 is a sectional detail showing a slight modification of the supports used for the plates and showing the insulation upon said supports.

30 Mounted within the jar 1 is a frame consisting of an annular base 2, of vulcanite, clay, or other insulating material, standards 3 4 5 6 7 8, preferably made of lead and "formed" or made of any other material corresponding 35 to the material of the battery-plates, and braces 9 10 11 12 of conducting material, these braces being so disposed as to connect the standards 3 4 5 6 7 8 in the manner indicated in Figs. 1 and 2. These braces 9 10 11

40 12 serve also as conductors, connecting the plates of each kind together. The terminals are shown at 13 and 14, each terminal, of course, being connected with plates of a particular kind. The plates 15 16 17 18 19 20 21 are all 45 made of the same shape and are provided with the ears 22, 23, 24, 25, 26, and 27. Each plate is of the form of a hollow truncated cone, the ears being flattened out for convenience in mounting the plates. Between adjacent pairs of ears are mounted annular sleeves 28 of material corresponding as nearly

as practicable to that of the plates and the standards.

Where the standards, sleeves, and plates are of substantially the same material, no insulation need be used between adjacent pairs of ears or upon the standards either above or below the plates. If, however, the standards are made of a material not acted upon by the battery fluid during the charging process, 55 they are preferably insulated, as indicated in Fig. 3, by tubes 29 and rings 30, of vulcanite. These tubes and rings should be neatly fitted upon the standards and may be temporarily cemented thereto, if desired, by means of 60 paraffin, wax, or other suitable plastic insulator. The annular sleeves 31 (shown in Fig. 3) may also be made of insulating material, if desired, the ears 32 being fitted directly upon the metal standards 33.

70 The battery-plates are so arranged that the ears of one group of plates—say the negative group—are in alinement with each other and alternate with the groups of ears of the positive plates. While all of the positive plates 75 are thus connected together and all of the negative plates are also connected together, the positive plates have no connection with the negative plates except through the medium of the liquid in the manner customary 80 in the ordinary use of storage batteries.

By the arrangement above described each of the battery-plates has such a form or shape that it will resist considerable shock and pressure and is not liable to buckle when charged 85 and discharged rapidly by the electric current. I find that plates of this form can be distorted considerably without injury. The conformity of such a plate enables it to yield without breaking, which is not the case with 90 plates having other arbitrary forms.

95 My invention has no relation to the material of which the plates are made. They may be made of lead and formed in the usual manner, or they may be built up by pasting grids As the methods of producing battery-plates for use in storage batteries are old and well known and have no relation to my invention I do not deem it necessary to describe them. 100 Suffice it to say that a battery-plate of the shape above described can be made by any

person skilled in the art of making battery-plates of other forms.

In the drawings each conical plate is provided with three ears, so that when the positive and negative plates are connected and the ears arranged alternately six ears will be seen from the top. I do not limit myself, however, to this particular arrangement, for obviously the plates may be disposed in other relative positions.

By the invention above described I am enabled to place in a single jar a great many battery-plates of large size, so as to produce a battery of considerable power inclosed with 15 in a small space, cheaply constructed, easily handled, and having all parts readily accessible. If a particular plate be damaged, it can be readily removed. A short circuit between the plates is easily detected, and any arbitrary 20 desired number of plates may be used.

Having thus described my invention, I claim as new and desire to secure by Letters Patent—

1. A storage battery, comprising a cylindrical cell for containing an electrolyte, a base of insulating material disposed therein, a plurality of standards of conducting material mounted upon said base, said standards being connected together in distinct groups 25 and said groups being provided with terminals, battery-plates of frusto-conical shape and provided with ears fitted upon said standards, and means for spacing said plates asunder.

35 2. A storage battery, comprising a cylin-

drical vessel for containing an electrolyte, an annular base of insulating material mounted therein and arranged substantially in the form of a circle, a plurality of standards of conducting material mounted upon said base, conductors connecting said standards together in distinct groups representing positive and negative members, terminals for said groups, and battery-plates connected with said standards and spaced asunder from each other, said plates being so connected together as to form two distinct groups, one of said groups of plates being in contact with one of said groups of standards, and the other of said groups of plates being in contact with the other of said groups of standards.

3. A storage battery, comprising a cell for containing an electrolyte, a frame mounted therein and provided with standards, battery-plates of hollow frusto-conical form and of 55 opposite sign mounted upon said standards, each of said battery-plates being provided with ears arranged in a plane, said ears engaging said standards directly, means for connecting said standards electrically together 60 in distinct groups, and terminals connected with said respective groups.

In testimony whereof I have signed my name to this specification in the presence of two subscribing witnesses.

HENRY P. KING.
